(57) **CLAIM**

We claim the ornamental design for a urinal, as shown and described.

DESCRIPTION

FIG. 1 is a perspective view of a urinal showing our new design;

FIG. 2 is a front view thereof;

FIG. 3 is a left side view thereof;

FIG. 4 is a right side view thereof;

FIG. 5 is top view thereof;

FIG. 6 is a bottom view thereof; and,

FIG. 7 is a rear view thereof.

The broken lines shown are for illustrative purposes only and form no part of the claimed design.
